UNITED STATES PATENT OFFICE.

FRANCIS H. RICHARDS, OF HARTFORD, CONNECTICUT, ASSIGNOR TO JEREMIAH EVARTS TRACY, OF NEW YORK, N. Y.

SEWING-MACHINE.

1,088,626.

Specification of Letters Patent.

Patented Feb. 24, 1914.

Application filed May 25, 1899. Serial No. 718,216.

To all whom it may concern:

Be it known that I, FRANCIS H. RICHARDS, a citizen of the United States, residing at Hartford, in the county of Hartford and State of Connecticut, have invented certain new and useful Improvements in Sewing Machines, of which the following is a specification.

This invention relates to sewing-machines, 10 an object being to provide an improved organization of stitch-forming mechanism which will permit the use, in a practical manner, of a reciprocatory needle and a two-hook rotatable looper.

15 A primary object of the invention is to provide means for receiving or taking a loop from one part of the stitch-forming mechanism—for instance, the needle—and holding the same in position to be taken by or transferring it to another part of such stitch-forming mechanism—for instance, an under-thread carrying device, such as a rotatable looper—whereby the needle can be substantially or completely out of the work before 25 the thread is pulled therethrough by such looper, and whereby also the dropping of a stitch is prevented and the consequent making of each successive stitch insured.

In the drawings accompanying and forming part of this specification, Figure 1 is a 30 longitudinal vertical sectional view illustrating a sewing-machine embodying my present improvements. Fig. 2 is a section on line α — α Fig. 1, looking toward the left. 35 Fig. 3 is a cross-sectional plan view of the operative parts below the bed-plate of the machine, with such bed-plate in dotted lines. Figs. 4, 6, and 8 are end views of the machine, looking toward the right and illustrating successive positions of the stitch-forming mechanism. Figs. 5, 7, and 9 are 40 top views of that portion of the stitch-forming mechanism located below the bed-plate and corresponding, respectively, with Figs. 4, 6, and 8. Fig. 10 is a side view of one 45 form of transerrer or needle-loop taker a part being in section. Fig. 11 is a top view thereof. Fig. 12 is an end view thereof looking toward the left; and Fig. 13 is a 50 cross-sectional view taken substantially in line α — α , Fig. 8, and showing the looper about to take a loop from the transerrer or needle-loop taker.

Similar characters of reference designate 55 like parts in all the figures of the drawings.

Heretofore, in practice, in those classes of sewing-machines using a rotatable looper, the needle-loop has been taken directly from the needle by such looper, this co-operation depending somewhat upon the throwing out 60 of a loop by the needle. Hence, when the needle-loop is not thrown out, owing to various causes—as, for instance, when the thread is kinky and twists around the needle, or the friction is not sufficient on the upward passage of the needle to form such loop—the looper fails to receive the loop and the stitch is lost. Moreover, since the needle must project sufficiently far through the work to permit the hooks of the looper to 70 take the loop adjacent to the eye of the needle, it follows that the looper draws the thread through the work simultaneously with the upward passage of the needle, which not only tends to fray and break the 75 thread, but also to materially retard the action of the machine, since the needle tends to wedge the thread in the work, thus retarding the drawing thereof therethrough by the looper. The improvement is designed for 80 the purpose of preventing this loss of stitch, and also to provide a machine to produce work more closely resembling hand-sewing—that is to say, a machine in which the needle will have passed substantially or entirely through the work before the drawing 85 of the thread through the needle-aperture, whereby the breakage of the thread is prevented—and for this purpose an improved means is provided adapted to receive or take 90 the loop from the needle and hold the same during the passage of the needle through the work, and to give or transfer the same to a device carrying the under thread—such, for instance, as a rotatable looper, and permit the same to draw the thread through the 95 work while the needle is out of the needle-aperture.

In the form of my invention, and which may be its preferred form, if desired, herein shown as applied to a sewing-machine the frame-work comprises a bed-plate 2, having a throat-plate 3, a depending looper-supporting bracket 4, and an upright hollow arm 5, at one end of said bed-plate and carrying a horizontal hollow arm 6, terminating in a needle-bar-receiving head 7.

The looper mechanism shown herein comprises a rotatable looper 8, of some suitable form, provided with a pair of loop-engaging 100

hooks or members 9. This looper 8 is supported in position for rotary movement by a guideway or track 10, formed as a part of the depending bracket 4, and is removable from said track on the removal of a retaining-plate 12, forming one member of said guideway. The looper is provided with a series of driver sockets 13 for the reception of the teeth or pins 14 of the driver 15, mounted on a driving-shaft 16, journaled at the under side of the bed-plate and which carries at its opposite end the usual driving-pulley 17. This looper-driving-shaft, which constitutes the main driving-shaft of the machine, is provided below the hollow upright arm 5 with a crank 18, for the purpose hereinafter set forth. The looper is shown supported obliquely to its driver, and in such position in the present instance that its hooks are relatively remotely disposed to the path of the needle being both below and at one side of the loop normally formed thereby.

The needle mechanism herein shown comprises a needle-bar 20, suitably guided in the head of the machine and carrying a needle 21 for reciprocatory movement. For driving this needle-bar and its needle a rock-shaft 20 is shown mounted in the horizontal arm 6 and provided with a crank-arm 22, connected with the needle-bar by a link 24, whereby on the rocking of said shaft the needle-bar is raised and lowered and thereby the needle.

For rocking the shaft it is shown connected with the main driving or looper shaft 16, and for this purpose such needle rock-shaft 20 is provided with an arm 25, rigidly secured thereto. Connecting this arm 25 with the crank 18 of the looper-shaft is a lever system, shown herein comprising a bell-crank lever or rocker 26, pivotally secured to the interior of the upright arm 5 and having its upper end linked to the arm 25 of the needle rock-shaft 20, and its lower end linked to the crank 18, whereby on the rotation of said driving shaft the rocker 26 will operate to rock the driving-shaft and thereby reciprocate the needle. This lever system is so organized that the needle will pass through the work twice for each rotation of the main driving-shaft and the looper and in time to permit a loop to be formed for each hook of said looper.

A suitable take-up device is provided, which in the construction shown is also operatively connected with the main driving-shaft. In the form shown this loop-take-up device comprises an arm 30, pivotally secured to an arm 31, fixed on a rock-shaft 32, mounted in the horizontal arm 6. This rock-shaft is connected by a rod 33 with a pivoted member 34, carrying a roll 35 in position to be engaged by a cam 36, mounted on the main driving-shaft, whereby on

the rotation of said shaft said cam operates to elevate said roll-carrying member and thereby actuate the rock-shaft. This loop-take-up arm 30 is provided with a pin 37, intermediate which and a pin 38, carried by the arm 31, is secured a spring 39. This loop-take-up arm 30 is also provided with an abutment to engage the pin 38 of said arm 31, whereby the take-up arm is movable with said rock-shaft, and, owing to its pivotal connection, independently thereof, such independent movement being limited by said spring.

Carried in the head is the usual adjustable presser-foot bar 40, having the presser-foot 41 for engaging the work and which may be shifted in any desired manner.

The work-feed mechanism, in the present instance, comprises a four-way feed, and in the form shown it comprises a feed-dog bar 42, the outer end of which is connected to a rock-shaft 43, mounted below the bed-plate, the opposite end of which shaft is connected to a forked member 44, the forked part of which extends around the main driving-shaft and carries a laterally-extending roll 45 in position to be engaged by a cam 46, mounted on said driving-shaft, said roll being held in engagement with said cam by a spring 47. By this mechanism, on the rotation of the main driving-shaft the cam is effective to shift the feed-dog in a horizontal path in one direction, while the spring is effective to return said feed-dog to its normal position and in this manner feed the material. To shift this feed-dog into and out of engagement with the work, it is shown connected intermediate its ends with another rock-shaft 48, mounted on said framework and to the opposite end of which is secured an arm 49, provided with a roll 50 in engagement with a cam 51, also mounted on the main driving-shaft, said roll being held in engagement with said cam by a spring 51', secured to said arm and to a fixture. On the rotation of said driving-shaft the cam 51 operates to shift the feed-dog in one direction, while the spring is effective to return it to its normal position.

It is to be understood that in practice the feed mechanism is timed, as is also the loop-take-up means, to properly effect the feed of the material and take up the loop after it leaves the looper.

In the present construction it will be observed that the looper does not receive or take a loop directly from the needle and that the hooks thereof, when in their loop-taking positions, are remotely disposed relatively to the path of the needle. For the purpose of receiving or taking a loop from the needle and holding it in readiness to be taken by or transferring it to said looper, suitable mechanism is provided, by means of which the taking of the loop each time by the looper is

positively insured. This means, in the present construction, comprises a transferrer (designated in a general way by A) adapted to pass intermediate the needle and its thread and form a loop for the looper with which it in turn co-operates. In the present instance this transferrer is so formed that it overlaps the periphery of the looper lying between it and the needle. In the present construction the transferrer is shown comprising a pointed member 60, shiftable into position to engage the thread of the needle and to transfer the same to the hooks of the looper. This member 60 comprises a loop-receiving or carrying portion or blade and a shank 67. Some suitable means adapted to shift this transferrer in the desired manner may be used to accomplish this object. In the present construction, however, this shifting operation is effected by the main driving-shaft through suitable intermediate instrumentalities, and for this purpose it is shown provided with a cam 61, effective to engage a roll 62, carried by a bifurcated arm 63, encircling said shaft, the opposite end of which arm is connected to crank 63' at one end of a crank-shaft 64. The opposite end of this rock-shaft is provided with a crank 64', a crank-pin 65, extending therefrom into a bifurcated or recessed portion 66 of the shank 67 of the transferrer, whereby on the operation of said rock-shaft by the cam the transferrer will be shifted into position to take a loop from the needle, it being returned into its normal position by a spring 68, fixed to the framework and to said bifurcated arm, and by means of which also the roll 62 is maintained in permanent engagement with its cam. During this shifting movement, it is desirable that the forward end of the transferrer shall have a movement downward from the needle toward the looper, so as to carry the loop into position to be engaged by the hooks of the looper, and to effect this movement in one way the transferrer is shown provided with a curved slot 163, receiving a projection or pin 164, carried by the framework, the rear end of said transferrer having a straight slot 165 to receive a corresponding projection or pin 166, which acts as a guide for the same. On the shifting of the transferrer the curvature of the slot 163 will, in a manner readily understood, co-operate with the pin 164 and shift the transferrer downwardly. It is also desirable that said transferrer shall have a movement laterally of or away from the needle horizontally in the plane of the loop, and for this purpose the transferrer is shown provided with a pair of curved slots 168, into which extend a pair of projections or pins 69, (shown herein carried by the projections 164 and 166,) whereby on the shifting of the transferrer the curvature of these

slots, in connection with the pins 69, will move the transferrer toward and from the needle in a manner which will be readily perceived. These slots constitute guideways, while the pins or projections constitute guides and in practice could be reversed so that the guides will be carried by the transferrer and the guideways by the framework. In the present instance the loop-engaging portion or blade 60 of the transferrer is shown of angular formation, having a grooved formation at its under side, whereby the thread is extended across the lower edges of the transferrer so as to permit the hooks of the looper to pass above the thread and so positively insure the taking of the loop. This construction also permits the transferrer to overlap the periphery of the looper and bring the same into closer relationship therewith. By the provision of this transferrer it will be seen that the hooks of the looper do not have to project laterally in order to be brought into close relationship with the needle, as heretofore, but such hooks may be formed midway of the sides of said looper, since the transferrer is shifted directly over its periphery.

In practice the needle may be provided with a groove or recess 70 to permit the point of the transferrer to pass between the needle and the thread. If desired, a guide 71 may also be provided, into which the point of the needle projects during the taking of the loop by the transferrer, whereby the bending or flexing of the needle and the missing of a stitch will be prevented.

From the foregoing it will be seen that the transferrer in the present instance is operated from the looper or main driving-shaft, being timed to take the loop from the needle at the proper time and to transfer the same to the looper, and that such transferrer has three movements—one longitudinally toward and from the needle in a plane intersecting that of the loop, another laterally toward and from the needle in the general plane of the loop, and the other downwardly and upwardly or in the same direction as the line of movement of the needle.

From the foregoing it will be seen that in operation the loop is taken directly from the needle by the transferrer and is conveyed into position to be engaged by the looper and removed by it from the transferrer, which takes place during the latter part of the passage of the needle through the work, so that when the looper commences to draw the thread through the work and to carry such loop around the same to be engaged by the under thread the needle may be substantially or completely through the work, so that the drawing of the thread therethrough is facilitated. It will also be seen that in the improved organization of mechanisms herein shown the looper, the

needle, the transerrer, the loop-take-up, and the work-feed may be all actuated from a single ordinary driving-shaft, and this without the use of gears or complicated mechanisms.

Having described my invention, I claim—

1. In a sewing-machine, the combination of stitch-forming mechanism comprising a needle and a two-hook rotatable looper; and means independent of the looper for transferring a loop from said needle to each hook of said looper.

2. In a sewing-machine, the combination of a rotatable looper having a plurality of hooks; a rotatable driving-shaft therefor; a needle; means connecting said needle with said driving-shaft and effective to reciprocate said needle through the work a plurality of times, corresponding with the number of hooks of said looper, for each rotation of said driving-shaft; and means independent of the looper for taking a loop from said needle and transferring it to each hook of said looper.

3. In a sewing-machine, the combination of a two-hook rotatable looper; a driving-shaft therefor; a needle; means connecting said needle with said driving-shaft and effective to reciprocate said needle through the work twice for each rotation of said driving-shaft, whereby a loop is formed for each hook of said looper; and means independent of the looper for taking a loop from said needle and transferring it to each hook of the looper.

4. In a sewing-machine, the combination of stitch-forming mechanism comprising a needle and a two-hook rotary looper; a driving-shaft for said looper; means for reciprocating said needle through the work twice during each rotation of said driving-shaft, whereby a loop is formed for each hook of said looper, and comprising a rock-shaft and a pivoted duplex lever linked to said rock-shaft and to said driving-shaft; and means for taking a loop from said needle and transferring it to a position where it will be engaged by a hook of the looper.

5. In a sewing machine, the combination of stitch-forming mechanism including a reciprocating needle and a looper located beyond the field of direct coöperation with the needle, a series of loop-taking elements mounted on said looper, and a mechanism for taking a loop from the needle and transferring it to the elements of the looper.

6. In a sewing machine, the combination with a reciprocating needle, of a rotatably mounted looper located beyond the field of direct coöperation with the needle, means for guiding said needle during a portion of its travel beneath the cloth plate, a transerrer which takes the loop directly from the needle, and means for advancing said transerrer in a circuitous path.

7. In a sewing-machine, the combination of stitch-forming mechanism; and a combined cam and spring actuated device for taking a loop from one part of said stitch-forming mechanism and transferring it to a position to be engaged by another part thereof which part is provided with a plurality of loop-engaging projections.

8. In a sewing-machine, the combination of a rotatable looper having a plurality of hooks; a driving-shaft therefor; a cam mounted thereon; needle mechanism; a transerrer for taking a loop from said needle and transferring it to each hook of said looper; and means in operative connection with said transerrer and in engagement with said cam for operating said transerrer.

9. In a sewing-machine, in combination with framework carrying projections; a looper; a driving-shaft therefor; needle mechanism including a needle located beyond the field of direct coöperation with the looper; a transerrer provided with a plurality of curved slots for the reception of said projections; and means for actuating said transerrer whereby said projections coöperating with said slots will effect the movement thereof in different directions.

10. In a sewing-machine, in combination with framework carrying projections; a rotatable looper; a driving-shaft therefor; needle mechanism including a needle; a transerrer provided with a plurality of curved slots for the reception of said projections; a rock-shaft connected with said transerrer; and means connecting said rock-shaft and driving-shaft to operate the transerrer on the rotation of said driving-shaft.

11. In a sewing-machine, the combination with framework, of two sets of intersecting projections carried thereby; a transerrer provided with two sets of slots, one set for each set of said projections; a rotatable looper; a driving-shaft therefor; needle mechanism including a needle; and means for operating said transerrer.

12. In a sewing-machine, the combination with framework, of two sets of intersecting projections carried thereby; a transerrer provided with two sets of slots, one set for each set of projections; a rotatable looper; a driving-shaft therefor carrying a cam; needle mechanism including a needle; means in engagement with said cam and connected with said transerrer, whereby on the rotation of said driving-shaft said transerrer is shifted; and means for maintaining said transerrer-connecting means in engagement with said cam.

13. In a sewing-machine, the combination of stitch-forming mechanism including a looper and a needle; and an angular transerrer adapted to move into position to

overlap the periphery of said looper and effective to take a loop from the needle and transfer it to a position away from the path of the needle where it will be engaged by said looper.

14. In a sewing-machine, the combination of stitch-forming mechanism including a rotatable looper and a needle; and a grooved transferrer adapted to take a loop from said needle and transfer it to a position where it will be engaged by said looper, the groove of the transferrer receiving the periphery of the looper.

15. In a sewing-machine, the combination with a two-hooked rotatable looper provided with a series of sockets; of a driving-shaft having a driver provided with driving-pins for successively engaging said sockets to rotate said looper; a reciprocatory needle; a rock-shaft connected therewith; means connected with said rock-shaft and with said rotatable driving-shaft for reciprocating said needle through the work twice for each rotation of the driving-shaft; a loop take-up operatively connected with said driving-shaft; work-feed mechanism operatively connected with said driving-shaft; and a transferrer also operatively connected with said driving-shaft for taking a loop from said needle and transferring it to each hook of said looper.

16. In a sewing machine the combination of stitch forming mechanism comprising parts each located out of the field of direct coöperation with the other, a frame work member having sets of intersecting projections, a driving shaft, a transferrer provided with sets of slots to receive said sets of projections, a rock shaft connected with said transferrer, and means in operative connection with said rock shaft and connected with said driving shaft for actuating said transferrer.

17. In a sewing-machine, the combination with stitch-forming mechanism comprising parts each located out of the field of direct coöperation with the other and a framework member having two sets of intersecting pro-

jections, of a driving-shaft carrying a cam; a transferrer provided with two sets of slots, one set for each set of said projections; a rock-shaft connected with said transferrer; and means in operative connection with said rock-shaft and in engagement with said cam for actuating said transferrer.

18. The combination with stitch-forming mechanism comprising a rotatable looper, of a loop-transferrer comprising a pointed, angular loop-receiving member adapted to overlap the periphery of the rotatable looper; a shank having two sets of slots; and projections engaging said slots.

19. In a sewing machine, the combination of a looper having a plurality of loop receiving devices preferably equidistantly disposed, a driving shaft therefor, a reciprocating needle adapted to so reciprocate as to coöperate with each of said loop receiving devices, means connecting the needle with said driving shaft and effective to reciprocate said needle through the work a plurality of times corresponding with the number of devices of said looper, for each rotation of said driving shaft, and means independent of the looper for taking the loop from said needle and transferring it to each device of the looper.

20. In a sewing machine the combination of stitch forming mechanism including a needle and a rotatable looper, a loop transferrer, means for moving said transferrer into the plane of movement of said looper for taking a loop from the needle and moving it bodily to one side thereof into position to be engaged by said looper, and driving connection between said needle, looper and transferrer moving means, constructed and timed for causing the needle to rise from the cloth prior to the transferring movement and for effecting coöperative looper movements.
